(73) Assignee: **VIVINT, INC.**, Provo, UT (US)

(57) **CLAIM**
The ornamental design for an “outdoor mount for home security system,” as shown and described.

(***) Term: **14 Years**

DESCRIPTION

(21) Appl. No.: **29/496,523**

FIG. 1 is a top perspective view of an outdoor mount for home security system according to the present invention;

(22) Filed: **Jul. 14, 2014**

FIG. 2 is a rear perspective view thereof;

(51) **LOC (10) Cl.** **08-05**

FIG. 3 is a front view thereof;

(52) **U.S. Cl.**

FIG. 4 is a right side view thereof;

USPC **D8/363**

FIG. 5 is a left side view thereof;

(58) **Field of Classification Search**

FIG. 6 is a top view thereof;

USPC D8/16, 18, 19, 20, 105, 356, 363, 366,

FIG. 7 is a bottom view thereof;

D8/370-377, 380-382; D6/406.2;

FIG. 8 is a rear view thereof;

D12/106, 48

FIG. 9 is a top perspective view of an alternative embodiment of an outdoor mount for home security system design according to the present invention;

CPC B25F 1/00; B25F 1/02; A45F 2200/0575;

FIG. 10 is a rear perspective view of the alternative embodiment thereof;

G01B 5/18

FIG. 11 is a front perspective view of the alternative embodiment thereof;

See application file for complete search history.

FIG. 12 is a right side perspective view of the alternative embodiment thereof;
